UNITED STATES PATENT OFFICE.

FREDERICK JONATHAN FISON, OF CAMBRIDGE, ENGLAND, ASSIGNOR TO CHIVERS & SONS LIMITED, OF HISTON, ENGLAND, A BRITISH COMPANY.

CLOSURE FOR JARS, BOTTLES, AND SIMILAR RECEPTACLES.

Application filed November 13, 1924, Serial No. 749,762, and in Great Britain May 27, 1924.

This invention relates to closures for jars and similar receptacles of the kind comprising a closing cap or cover of sheet metal or other suitable thin material having a depending flange or skirt which is used in conjunction with a flat rubber gasket which is interposed between the upper surface of the jar neck and the said cap or cover, which latter is retained in the closed position with the gasket pressed close against its seating on the jar by atmospheric pressure due to air being exhausted from the jar by a vacuumizing process.

According to this invention, the said flange or skirt of the sheet metal cap is provided with a slit between the upper and lower edges of the said flange or skirt at such position that the portion of the flange above the slit covers the outer edge of the gasket whilst the slit itself lies adjacent to a rounded part of the jar neck, the said slit being wide or long enough to enable an ordinary table knife to be inserted through the same so that it is guided by the rounded part of the jar neck and directed between the gasket and its seating on the jar so as to break the seal and destroy the vacuum within the jar. The knife can be passed beyond the seating towards the diametrically opposite part thereof so that it can be manipulated to remove the cap after breaking the seal thus enabling the breaking of the seal and the removal of the cap to be effected in practically one operation whilst the knife is positioned within the aforesaid slit. The cap may be provided with peripheral retaining means such as hook-like tabs on or depending from the cap flange or skirt for enabling the cap to be retained on the jar by a length of string or similar flexible material which is passed alternately over the said retaining means and under a shoulder or beading on the jar in substantial circumferential contact therewith, so that by pulling the string tightly and tying or securing its ends a downward pull is exerted on the retaining means for the purpose of retaining the cap on the jar in case the vacuum seal should be broken accidentally. This method of retaining the cap on the jar forms the subject of my earlier application for United States Patent Serial No. 715,991 filed 26th May 1924.

In order that the invention may be clearly understood and readily carried into effect,

the same will now be more fully described with reference to the accompanying drawings, in which:—

Figure 1 illustrates a construction of the improved cap having peripheral retaining means that can be engaged by a securing string as aforesaid.

Figure 2 is an enlarged fragmentary sectional view taken through the slit in the peripheral skirt or flange on the cap.

A represents a jar having a rounded shoulder or beading A¹ at its upper part, the cross sectional form of which is as shown in Figure 2. B indicates the closing cap or cover which is in the form of a sheet metal disc having a peripheral depending flange or skirt B¹, whilst it is also shaped to provide a recess B³ at its outer part to receive a flat gasket or packing ring C of rubber, which, when the cap is placed on the jar, rests on the upper surface of the jar shoulder or beading A¹ as shown in Figure 2.

The cap flange or skirt B¹ is provided with a wide slit B² between the upper and lower edges of the said flange or skirt B¹ and the so part of the flange above the said slot extends to or slightly beyond the lower surface of the gasket so as to protect or cover the outer edge of the gasket. When the jar with the cap applied, is subjected to the vacuumizing process the cap is drawn tightly on to the jar, thereby causing the gasket to be pressed closely on to the upper part of the shoulder or beading to effect a seal which is maintained after removal of the jar from the vacuumizing apparatus by atmospheric pressure. A portion of the rounded shoulder or beading A¹ on the jar is exposed through the said slit B² which is large enough to receive the end of an ordinary table knife, which, when inserted in the said slit is guided by the exposed rounded portion of the jar shoulder A¹ so that it can be thrust between the under surface of the gasket and the upper part of the shoulder for the purpose of breaking the vacuum seal so as to destroy the vacuum and thus permit of the cap being readily removed. The knife can be thrust through the slit B² to a substantial extent across the jar so that after breaking the seal it can be manipulated to remove the cap whilst still within the slit so that it is unnecessary to withdraw the knife from the slit after breaking the seal and before taking off the cap. the example shown the peripheral skirt of the cap is provided with depending hook-like tabs or projections D which can be passed over the maximum diameter of the jar shoulder A¹ so as to grip against or under the latter. A string D¹ may be passed over the said hook-like tabs D and tied circumferentially around the jar under the shoulder so that by reason of the engagement of the string under the said shoulder a downward pull can be exerted on the hook-like tabs so as to secure or retain the cap on the jar in case the vacuum seal should be accidentally destroyed or broken. This feature of affording additional security by passing the string over hook-like tabs or the like on the cap and under the shoulder of the jar is described in the specification of my prior United States patent application Serial No. 715,991. Any of the peripheral retaining means for the string as disclosed in the specification of my prior patent application may be provided on the peripheral skirt or flange of the cap according to this invention and the said slit for the insertion of the table knife is in all cases located between a pair of the retaining means, as shown in Figure 1. The cap having the depending tabs or the like that pass over the maximum diameter of the shoulder and grip the latter can be used as a re-seal cover or closure after initial removal of the cap. When initially removing the cap retained by the securing string as aforesaid, the string can be first cut with a table knife and whilst this is in the hand it can be inserted through the slit B² to break the vacuum seal and remove the cap.

What I claim and desire to secure by Letters Patent of the United States is:—

1. A jar or similar closure of the vacuum seal type comprising a closing cap of thin material having a depending peripheral flange and a gasket adapted to be interposed between the upper rounded edge of the jar neck and said cap, the said flange on the cap having a slit between its upper and lower edges, in such position that the portion of the flange above the slit covers the outer

edge of the gasket, whilst the slit itself 50 lies adjacent to part of the rounded edge of the jar neck and is made long enough to enable an ordinary table knife to be inserted through the same and guided by the said rounded part of the jar neck so as to 55 be directed between the gasket and its seating in order to break the seal and destroy the vacuum within the jar.

2. The combination with a receptacle having an enlarged bead about its mouth, of a 60 closure of the vacuum seal type comprising a cap of thin material provided with a depending flange, and a gasket within the cap adjacent the flange thereof and bearing on the bead about the mouth of the receptacle, the flange of the cap being provided with a slit positioned in substantial alignment with one of the faces of the gasket, and through which a blade like instrument 65 can be inserted to break the seal provided 70 by the gasket.

3. A jar closure of the vacuum seal type comprising a cap of thin material provided with a depending flange, and a gasket within the cap adjacent the flange thereof, the 75 flange being provided with a slit positioned in substantial alignment with one of the faces of the gasket, and through which a blade like instrument can be inserted to break the seal provided by the gasket when 80 the closure is in use.

4. The combination with a receptacle, of a closing cap having a peripheral flange surrounding the upper end of the receptacle and provided with a plurality of hooks, a 85 gasket between the cover and upper edge of the receptacle, and a flexible binder cooperating with said hooks and means on the receptacle to retain the cover in position, the peripheral flange of the cover having 90 formed therein a slit in substantial alignment with the inner face of the gasket through which a blade-like instrument can be inserted to break the seal between the gasket and receptacle when the flexible binder 95 has been released.

FREDERICK JONATHAN FISON.
